United States Patent Office

Des. 180,764
Patented Aug. 13, 1957

180,764

BRASSIERE

Robert Gustav Brauchli, East Orange, N. J.

Application September 20, 1956, Serial No. 43,017

Term of patent 14 years

(Cl. D20—4)

Fig. 1 is a front elevational view of a brassiere showing my new design, and

Fig. 2 is a rear elevational view thereof.

I claim:

The ornamental design for a brassiere, as shown.
